TOOL FOR HANDLING RETAINING RINGS

Rudolf Feitl, Brooklyn, N. Y., assigner to Waldes Koh-I-Noor, Inc., Long Island City, N. Y., a corporation of New York

Application August 11, 1944, Serial No. 549,056

3 Claims. (Cl. 29—223)

1

This invention relates to improvements in plier-type tools for handling open-ended retaining rings.

As is well known, difficulties are encountered in handling open-ended retaining rings of the type adapted to be sprung into the groove of a shaft or housing, in view of the requirement that such rings must be spread or compressed in slipping them over the shaft or when inserting them into the housing in which they seat. To assist in handling such rings, it has been proposed in Reissue Patent No. 18,144 to provide such retaining rings at their open ends with apertured ears or lugs, so that the points of pliers can be inserted into the apertures and the ring spread or compressed, depending on whether it is of the external or internal type. In spreading an external ring so that it can be slipped over a shaft and into its seating groove, care must be taken in providing against over-spreading of the ring which might cause ring breakage or permanent set. Moreover, the disassembly of a spring ring which is seated under spring pressure in its groove is a complicated operation, particularly if a ring face abuts against the adjacent surface of the machine part held thereby, so that the plier points can be inserted into the ear apertures only the amount corresponding to the thickness of the rings which, for small rings, is correspondingly small. In such cases, the friction between the plier points and the edges of the ear apertures is not sufficient to provide adequate grip on the ring so that it can be spread or compressed to lift it from its groove.

The object of the present invention, stated broadly, is to provide a simple form of pliers for handling open-ended retaining rings which overcomes the difficulties in handling as above noted. More specifically, the invention contemplates and provides a plier-type tool of particular advantage in handling retaining rings of the external type according to which the danger of ring breakage or of imparting permanent set thereto is diminished, if not avoided entirely. The invention also has for its object the provision of a plier-type tool for handling retaining rings having apertured ears at the open ends thereof, by which a firm two-point grip of the ears may be obtained, thus to facilitate spreading and thereupon lifting of the ring from its groove against holding pressure exerted by the groove wall or an abutting machine part. A further object of the invention is to provide a plier-type tool for firmly gripping the ears conventionally provided on open-ended retaining rings and for simultaneously limiting

2

the amount of spreading (or compressing) of the ring. Yet another object of the invention is to provide a plier-type tool provided with means for limiting the amount of spreading or compressing of the ring as aforesaid and which moreover incorporates means whereby the first-mentioned means may be so adjusted that one set of pliers can be used in handling a wide range of ring sizes.

Other objects will be in part obvious and in part hereinafter pointed out in connection with the following analysis of the invention wherein are illustrated in detail embodiments of the invention selected for simple description.

15 In the drawings—

Fig. 1 is a part perspective view of a tool according to the invention shown in its operation of spreading a typical retaining ring of the open-ended type;

20 Fig. 2 is a plan view of the tool partly illustrated in Fig. 1, illustrating the normal position of the tool and jaw points;

Fig. 3 is a section taken along line 3—3 of Fig. 2;

25 Fig. 4 is a view corresponding to Fig. 2 illustrating the tool points in their spread position, Fig. 5 being a section along line 5—5 of Fig. 4;

30 Figs. 6 and 7 are part plan views of a modified tool according to the invention, Fig. 6 illustrating the tool points in their normal position and Fig. 7 illustrating said points in their spread position;

Fig. 8 is an end view taken from the left end of the tool illustrated in Fig. 6;

35 Fig. 9 is a part plan view illustrating another form of tool according to the invention, Fig. 10 being a section thereof taken along line 10—10 of Fig. 9.

Referring to the drawings, wherein like reference characters designate like parts throughout the several views, Figs. 1—5 illustrate one form of tool according to the invention which is provided with working tips 10 and 11 terminating at their one end in points 12, 13 and being joined at

45 their other end to operating handles 14, 15. The tips are pivoted in a frame 16 which is shown to be of flattened tube section, by pins 17, 18 so that movement of the handles towards each other results in spreading of the tip points 12, 13. In the 50 normal position of the tool, the handles are spread by a spring 20 (Figs. 2 and 4) and the tips 10 and 11 accordingly engage along their adjacent inner edges which are formed straight. To insure that the tips in their normal position are 55 centered on the longitudinal center line of the

tool, the frame 16 carries a centering pin or rivet 22 disposed on the tool center line, against which the adjacent edges of the tip normally bear under the urge of spring 20.

According to the invention, the frame 16 is provided with channeled arms 24, 25 which are disposed outwardly of and closely adjacent to the opposite sides of the tips 10 and 11; the arms terminating substantially at the working points 12, 13 in jaws 26, 27 which are disposed outwardly and in the path of movement of the points. As indicated in Figs. 2-5, the tool tips 10, 11 move into the channeled arms as they are spread by compression of the handles 14, 15.

As shown in Figs. 1 and 4, the jaws 26, 27 provide abutments against which apertured ears as conventionally formed at the open ends of a retaining ring R are gripped as the ring is spread by the operation of inserting the tip points 12, 13 into the apertures of the ring and thereupon compressing of the handles to spread the working tips. Accordingly, the ears of the spread ring are firmly gripped between the tool point 12 and the jaw 26, on the one side; and between a tool point 13 and the jaw 27, on the other. It will be observed, moreover, that the jaws 26, 27 are spaced a given fixed distance; and hence function to limit the amount that the ring can be spread. By a proper choice of the spacing between jaws 26, 27, overspreading of the ring as is liable to result in ring breakage or of permanent set thereof is prevented.

Accordingly, a tool as described not only facilitates handling of the ring by providing a firm two-point grip on the ears formed at the open ends thereof, whereby the ring can be easily lifted from its groove against forces tending to frictionally bind the same to the sides of its seating part held thereby, but also operates in such manner as to prevent over-spreading of the ring in the normal handling thereof during assembly or disassembly.

Referring to the modification illustrated in Figs. 6, 7 and 8, the working tips 30, 31 are pivoted to each other at 32 and are spread by handles 33, 34, in manner similar to the tool previously described, against the bias of handle spring (not shown) corresponding to spring 20 (Figs. 2 and 4). The ends of the tips are formed as points 37, 38, adapted to be inserted into the apertures or slots of the ears conventionally formed at the open ends of retaining rings and thus function in manner similar to the points 12, 13, shown in Fig. 1.

To provide for adjustment of the spacing between the abutment jaws characterizing the present tool, the jaw-carrying arms 40, 41 are pivoted to the tips 30, 31 by pins 42, 43 and thus have angular movement relative to the tips whereby the spacing between their jaws 44, 45 may be varied. As shown, the means for imparting angular movement to the jaw members 40, 41 may comprise a U-member 46, the side legs of which are secured to one of the jaw members, for example, jaw member 40, so that the U-member straddles the other jaw member 41. The cross or bridge part 47 of the U-member is provided with a threaded aperture for the reception of bolt 48 having a winged head 49 to facilitate turning thereof. The axial position of the bolt may be adjusted through rotation of the winged head, a locknut 50 threaded on to the bolt 48 being provided to secure the latter in its adjusted position.

By the aforesaid arrangement, the distance be-

tween the side edge of the jaw member 41 and the end of the bolt 48 which determines the maximum spacing between the outer jaws 44, 45, and hence the amount that the open ends of the ring can be spread by the tip points 37, 38, is variable. Accordingly, a tool as described can be adjusted for use with different size rings, through the simple procedure of adjusting the bolt 48 for the maximum amount that a ring of given size can be spread.

As with the tool illustrated in Fig. 1, the working tips 30, 31 according to the present embodiment are centered by a pin 51 carried by the U-member 46 on the longitudinal center line of the tool and extending between the adjacent edges of the tips.

In the variant illustrated in Figs. 9 and 10, wherein is shown a tool according to the invention provided with another form of adjusting the distance between abutment jaws, the tool tips 60, 61 are pivotally carried at 62, 63 by a frame member 64 shown to be a rectangular plate. The tips are provided at their working ends with points 66, 67 and are spread by handles 68, 69 secured to their other ends. The tips are centered by a pin 70 carried by the frame 64 to lie on the longitudinal center line of the tool.

Jaw carrying arms 71, 72 corresponding to the jaw members 40, 41 of the Fig. 6 modification, and provided at their free ends with jaws 73, 74, are pivotally carried by the frame plate 64 preferably by the same pins 62, 63 which provide pivotal mounting for the tips 60, 61.

To provide adjustment of the angular position of jaw members 71, 72 relative to the tool tips 60, 61, the frame plate 64 is slotted as at 75 for the passage of threaded studs 76, 77 carried by the jaw members 71, 72, respectively, to project through the plate slot 75 (Fig. 10). Threaded on to the studs 76, 77 are securing nuts 79, 80 operating to secure the lower ends of the jaw members in adjusted position relative to plate 64 and hence to tool tips 60, 61.

By unloosening the nuts 79, 80, the jaw members may be moved about their pivots 62, 63 an amount establishing the desired distance between the jaws 73, 74; the adjusting studs 76, 77 traveling in the plate slot 75 during such angular movement. Thereupon, the nuts 79, 80 are tightened to secure the jaws in their adjusted position. Accordingly, a tool as described may be used with rings of varying sizes to limit the amount of spreading permitted the ring, and also to effect firm two-point gripping of the ring ears between the tip points 66, 67 and the jaws 73, 74.

While the tools according to the foregoing description are of the type in which the tool points are spread to effect spreading of a ring of the external type, either to seat it in its groove or to lift it from the groove for disassembly purposes, it will be understood that the principle of the described tool may be applied without substantial modification in the design of a tool for handling rings of the internal type, i. e., rings which must be compressed in order to be slipped into the groove of a housing or the like.

As many changes could be made in carrying out the above constructions without departing from the scope of the invention, it is intended that all matter contained in the above description or shown in the accompanying drawings shall be interpreted as illustrative and not in a limiting sense.

I claim:

1. A plier-type tool for handling open-ended

retaining rings provided at their ends with apertured ears comprising a pair of uncrossed levers and pivot means operatively connecting said levers intermediate their ends, the ends of the levers to one side of the pivot means constituting plier tips terminating in pin-like working points adapted to be inserted into the ear apertures and the other ends constituting handles to spread the working points and thereby the ends of the rings, a pair of arms disposed outwardly of and extending closely adjacent to and along the opposite sides of the plier tips and in the path of spreading movement thereof, each arm being pivotally connected adjacent its one end to one of said levers, the other ends of the arms terminating substantially at the working points and being formed as jaws which are disposed outwardly and in the path of movement of the working points, and means extending between and operatively engaging each of said arms at points spaced from their pivotal connections to limit their spreading movement to a predetermined distance, said means including adjustable means for varying said distance as desired, said jaws adapted to engage the apertured ears of a ring being spread by said working points and to limit the movement thereof whereby each ear is gripped by a jaw and its corresponding working point.

2. A plier-type tool as set forth in claim 1, wherein said adjustable means comprises a U-member affixed to one arm and straddling the other arm, and an adjusting screw threaded through the cross part of the U-member to cooperate with said other arm and whose setting determines the maximum spreading movement of said arms.

3. A plier-type tool for handling open-ended retaining rings provided at their ends with apertured ears comprising a frame member, a pair of levers and a pair of arms having pivotal connection with said frame member intermediate their ends, the ends of the levers to one side of their

pivotal connection with the frame constituting plier tips terminating in pin-like working points adapted to be inserted into the ear apertures, and the other ends constituting handles to spread the working points and thereby the ends of the ring, the arms extending closely adjacent to and along the opposite sides of the plier tips and in the path of spreading movement thereof, the arms terminating substantially at the working points

5 in end jaws disposed outwardly and in the path of movement of the working points, and adjusting means for spacing the arms a variable fixed distance apart whereby the jaws are effective to limit spreading of the ring and to provide abutments

10 against which the edges of the ring ears are adapted to be gripped when the ring is spread as aforesaid, said spacing means comprising adjusting screws carried by the other ends of said arms, said screws extending through a slot provided in the frame member, and securing nuts cooperating with said screws for securing said arms in desired adjusted position to the frame along the length of the slot.
